UNITED STATES PATENT OFFICE.

MAURICE PIERCE, OF BERGEN, NORWAY.

LIFTING JACK.

Application filed January 15, 1927. Serial No. 161,449.

The objects of my present invention are briefly as follows:

To provide a support or holder which will receive the axles of vehicles when presented at various elevations without the necessity of previous adjustment in preparation for the different heights. The receipt of the weight to be accomplished without shock or jar especially when the weight of the vehicle is automatically transferred from a primary lifting plane placed under the wheel.

Further, to provide the support with a sliding base which will enable it to move over the ground after receiving a weight thus avoiding a strain on the device or to the vehicle until such time as the momentum is exhausted.

To construct the device in such manner that the weight may be retransferred to the ground through the reemployment of a tilting inclined plane, inserted under the wheel and inclining in the opposite direction from that in which it was first placed for elevating.

To enable the device to collapse at will when a weight is being supported as well as when the device is not in use.

To enable the device when collapsed to be folded compactly together for storing in a small space.

To be quickly made ready for use and likewise quickly collapsed and folded.

To have bases wide enough to prevent the device from falling over sidewise.

To provide the bases with runners or guides on their under surfaces which will cause the device, when sliding to move in a straight longitudinal path.

To provide the upper bearing surface of the device with a combined shock absorbing and non-skidding material which may easily be removed when worn and a new surface attached, thus offering protection to the axle of the vehicle and to the device as well as preventing the former from slipping backward on the latter.

The device to be light in weight, strong, durable, easy to operate, but which will not get out of order and which will remain clean.

These objects and others I accomplish in

the following manner described and claimed and by use of the parts fully illustrated by the accompanying drawings.

In the drawings:

Figure 1 is a side elevation of the improvement in operative position.

Figure 2 is a top plan view thereof.

Figure 3 is a rear end view thereof.

Figure 4 is a sectional view on the line 4—4 of Figure 1.

Figure 5 is a side elevation of the improvement in folded or collapsed position.

Figure 6 is a detail sectional view approximately on the line 6—6 of Figure 7.

Figure 7 is a plan view of a part of the construction illustrated in Figure 6.

Figure 8 is a perspective view to illustrate the hinged connection between the plane sections.

An inclined plane of slightly less than two feet in maximum height and approximately three feet in length is formed of two sections of U steel 1 and 2 with their concave surfaces facing upward and rigid back surface downward. These two plane sections are attached together by means of two plate hinges 3, which are fastened with pivots 4 and 5. Strips of wood or other filling material 6 are packed in the U-shaped sections on their inside bottoms and may be secured by rivets 7.

A shock absorbing and non-skidding upper surface 8, illustrated in form of a piece of ordinary hemp rope, is inserted into the U-shaped steel plane and is held fast at either end by screw fasteners 9, and near its middle by the hinge pivot bolts 4 and 5, which pierce the rope as they pass through from one side of the plane to the other. Where the two sections of the plane come together near the middle, their ends are notched, as at 10. At the lower extremity of section 1, the plane rests upon a broad upturned sliding base 11, which has runners or guides 12 on its under surface. This base is attached to the plane by means of a pivot bolt 13, which permits the base to swing into line with the plane as illustrated in Figure 2, but which when ready for use permits the wide base to be held at a 90 degree angle to the plane with the assistance

of a drop key 14, which swings on a pivot bolt 15, the latter being inserted near the lower extremity of section 1 of the plane.

This key drops into a cut out section 16, 5 in the rear upturned portion of the wide base, and prevents the latter from swinging or pivoting until such is desired.

The upper or apex extremity of the inclined plane is held in its elevated position 10 by an upright support 17, constructed preferably of light, strong metal, illustrated as a section of U-shaped steel. The upright support section 17, is provided with apertures 18, at its upper extremity into which a pivot bolt 19 is inserted and passes through the upper end of the inclined plane.

The upright support 17, is mounted on a sledge like base 20, to which it is firmly attached by means of rivets 21.

20 The base 20 is constructed of a section of light, strong channeled metal which is upturned in ski-like fashion at its two ends, 22, and its under flanges 23 form runners or guides for straight sliding purposes.

25 A middle support 24 is swingably attached to the base 20, by means of a pivot bolt 25, inserted in apertures 26, in the upper flanges or extensions thereon of the base 20, the said bolt also passing through the lower extremity of the middle support 24.

30 The middle support is shown constructed of a section of light, strong U-shaped metal similar in material and dimensions to that used for the upright support 17. The concave sides of the supports 24 and 17 face each other and when the middle support 24, is swung in the direction of section 17, a box or hollow case is formed within which the plane sections 1 and 2, may have been previously collapsed, as will hereinafter be fully set forth.

35 The middle diagonally upright support or brace section 24 is designed to give support to the hinged and notched joint, 10, formed at the middle where the two plane sections 1 and 2, come together.

40 This support is formed as shown in the drawing by slitting the upper back face of support 24, as at 27, and a small section of this back face bounded by the slits is bent out to form a resting flange or ledge 28, while the sides of the middle support 24 extend upward on each side of the plane section 2.

45 An aperture 29 is drilled through the upper extremity of the middle support and passes horizontally through both sides of the plane section 2, just between the bottom face of plane section 2 and its upper non-skidding surface attachment. This space has been shown as filled with wood or other packing and the hole will consequently pass through this substance as well.

50 A pin bolt 30 is provided for insertion into the aperture 29, to prevent the middle

support 24, from falling or sliding away from its position of support. Immediately under the notched joint the pin bolt 30 is attached to the middle support by means of a hole or eye rivet 31, and a cord or small chain 32.

The pin bolt 30, will be inserted when the device is being made ready for use and extracted when ready to be folded. A light strong chain or piece of cable 33, is attached to the base upon which the supports 17 and 24 are mounted by means of a small rivet or screw eye 34, inserted through an aperture 35, in the rear upturned end of the base and the opposite end of this chain or cable is attached to the lower extremity of the plane by means of an eye screw or rivet 36.

This chain or cable is obviously for the purpose of preventing the two bases from spreading away from one another when the device is supporting a heavy weight. A swinging hook 37, is riveted or screwed to the support 17, and an eye loop 38 similarly attached to the support 24.

55 The collapsing of my device is accomplished almost instantly by removing the pin bolt 30, whereupon the middle support 24 falls or is thrust downward. The notched joining ends of the planes 1 and 2, collapse downward until the notched end of section 2 of the plane is folded within the hollow support 17, at the lower extremity of the latter.

60 The notched end of the plane section 1 follows suit and finds itself folded downward on the top of the base 20.

Now the wide base 11 is swung on its pivot 13, into line with plane section 1 and the base end of plane section 1 is found already swung upward to a position close to the top of support 17. The hollow support 24, as previously mentioned is now swung back in the direction of support 17, and the swinging hook 37, is hooked into the eye loop 38. We thus have plane sections 1 and 2, first collapsed, second folded, and third, encased within the hollow supports 17 and 24.

65 My improvement is especially designed to operate in conjunction with a primary elevating plane which is placed in the path, of one wheel at a time, of advancing vehicles.

70 The receiving and supporting plane above described has demonstrated for the inventor its ability to automatically receive, advance, support, transfer, and lower heavy weights without shock, strain or injury to the vehicle or the device. Its sliding base feature is considered novel in a device of this kind. All other devices of this kind, within my knowledge have depended, in one or another manner, upon their ability to hold fast to the ground before or after they are to, or have re-

ceived weights. Such devices have not proven successful since they firstly will not remain in proper position, secondly, will not automatically receive, and thirdly if able to suddenly check the advancing weight, the shock will prove injurious to both the vehicle and the device.

By experimenting I have discovered that a remarkably steep angle can be used for the supporting plane before any back sliding will take place on the part of the elevated axle. This is true without the application of emergency or other brakes, and when the latter is employed as a precaution, the possibility of back slide is entirely eliminated. The fact must not be overlooked that the heavy weight of the car, resting on three other points, namely, the three other wheels, must be thrust backward before the axle can slide backward on the plane and it must also be borne in mind that the initial momentum was only horizontally forward and downward. When at rest the emergency of gravity is exerting itself in a direct downward direction.

Having described the invention, I claim:

1. In a device for the purpose set forth, an inclined plane having a friction surface, and comprising two hinged sections, a vertical brace pivotally secured to the elevated end of the plane, a support removably secured to and supporting the joint between the plane sections and said supports providing a housing for the plane when the sections thereof are folded.

2. In a device for the purpose set forth, an inclined plane having a friction surface and comprising two hinged sections, a hollow vertical support to which the elevated end of the plane is pivoted, a hollow pivotally supported brace swingable to contact with the plane designed to be removably secured thereto and to support the joint between the plane sections, and said plane when folded designed to be housed between the brace and support.

3. In a device for the purpose set forth, an inclined plane having a friction surface and comprising two hinged sections, a hollow vertical support to which the elevated end of the plane is pivoted, a hollow pivotally supported brace swingable to contact with the plane designed to be removably secured thereto and to support the joint between the plane sections, and said plane when folded designed to be housed between the brace and support, and means for latching the support and brace when the plane sections are folded therebetween.

4. In a device for the purpose set forth, an inclined plane having a friction surface and comprising two hinged sections, a channeled vertical support in which the elevated end of the plane is pivoted, a channeled pivotally supported brace having

an outstanding flange, and its sides extending beyond said flange to contact with the sides of the plane and to permit of the flange underlying the joint between the plane sections, removable means for securing the brace to the plane when in bracing position, said plane sections designed when folded to be housed between the support and brace, and means for latching the brace to the support when the plane is folded therebetween.

5. In a device for the purpose set forth, an inclined plane having a friction surface and comprising two sections, straps having their ends pivotally secured to the confronting ends of the said sections, a vertically disposed channeled support in which the elevated end of the plane is pivoted, a pivotally supported channeled brace having an outstanding flange and its sides extended beyond the said flange, to embrace the sides of the plane and to permit of the said flange underlying the joint of the plane sections, a flexibly supported pin on the brace designed to be passed through the projecting sides thereof and through one of the plane sections, said plane, when folded, designed to be housed between the support and the brace, and latch means carried by the support for engaging the brace when the plane is folded therebetween.

6. In a device for the purpose set forth, an inclined plane comprising a channel member having a friction surface therein whose ends are removably secured thereto and whose outer surface projects therefrom, said plane comprising two hinged sections, a channeled support in which the elevated end of the plane is pivoted, a pivotally supported channeled brace swingable to engage with the plane and to support the joint between the sections thereof, removable means holding the brace in such position, and said support and brace providing a housing for the plane when the sections thereof are folded.

7. In a device for the purpose set forth, an inclined plane comprising a channeled member, made up of two hinged sections, a friction element comprising a rope received in the channel of the plane, having its ends removably secured thereto and its outer surface projecting therebeyond, a pivotally supported laterally extending base for the lower end of the plane, a swingable latch on the plane engageable with the base for holding the same laterally with respect to said plane, a skid, a channeled support having one end fixedly secured on the skid, and its upper portion receiving therein the elevated end of the plane, a pivot connecting the support to the plane, a channeled brace pivotally supported on the skid, and swingable for contact with the sides and with the base of the plane to support the joint between the plane sections, means

for removably securing the brace to the plane, and said support and brace providing a housing for the plane when the sections of said plane are folded together.

8. In a device for the purpose set forth, an inclined plane comprising a channeled member, made up of two hingedly connected sections, a friction element comprising a rope received in the channel of the plane, having its ends removably secured thereto and its outer surface projecting therebeyond, a pivotally supported laterally extending base for the lower end of the plane, a swingable latch on the plane engageable with the base for holding the same laterally with respect to said plane, a skid, a channeled support having one end fixedly secured on the skid, and its upper portion receiving therein the elevated end of the plane, a pivot connecting the skid to the plane, a channeled brace pivotally supported on the skid, and swingable for contact with the sides and with the base of the plane to support the joint between the plane sections, means removably securing the brace to the plane, said support and brace providing a housing for the plane when the sections of said plane are folded together, and a flexible connection between the skid and the lower end of the plane.

9. In a device for the purpose set forth, an

inclined plane having a friction surface and comprising hinged sections, supporting and bracing means for the plane, and said means providing a housing for the plane when the sections thereof are folded.

10. In a device for the purpose set forth, an inclined plane comprising two hingedly connected sections, a comparatively wide base to which the lower end of the plane is pivotally secured, said base having its edges beveled upwardly and its outer face provided with spaced transversely extending ribs, and one of said edges having a central notch, a pivotally supported gravity influenced dog carried by the plane and engageable within the notch, a skid comprising an eye beam having its ends rounded upwardly, a fixed support in the skid to which the elevated end of the plane is pivoted, a pivoted brace on the skid engageable with the plane at the joint between the sections, removable means for latching the brace to the plane, a removable and adjustable flexible connection between the lower end of the frame and the skid, and said brace and support providing a housing for the plane when the sections of the latter are folded therebetween.

In testimony whereof I affix my signature.

MAURICE PIERCE.
